UNITED STATES PATENT OFFICE.

HENRY BERGER, OF NEW YORK, N. Y.

DESIGN FOR CENTER-PIECE.

Specification forming part of Design No. 7,359, dated April 7, 1874; application filed March 27, 1874.
[Term of Patent 14 years.]

F.

To all whom it may concern:

Be it known that I, HENRY BERGER, of the city, county, and State of New York, have invented a new and original Design for Center-Piece; and I do hereby declare the following to be a full, clear, and exact description thereof, which will enable those skilled in the art to make and use the same, reference being had to the accompanying drawing forming part of this specification, which drawing shows a face view of my design.

This invention relates to the design of a central button surrounded by a series of radiating foils, inclosing alternate clusters of pearls and spear-heads, and which are inclosed by a square bead, the corners of which are broken and ornamented by escutcheons, between which are scrolls supporting a spread leaf.

In the drawing, the letter A designates the central button of my design, which is ornamented by a string, *a*, of pearls. Outside of this button are bunches or clusters *b* of pearls, and spear-heads *c*, which alternate with each

other, and are contained within foils or segments B. These foils are inclosed by a bead or rim, C, having broken corners or angles, which are ornamented by escutcheons D, the whole being of a square shape or outline. Midway between each two of the corners or escutcheons D is a twist or scroll, E, on which rests a leaf, *b*, in a spread condition.

What I claim as new, and desire to secure by Letters Patent, is—

1. The combination of the circular series of foils B with the central button A, as shown and specified.
2. The combination of the square bead C, escutcheon D, and scrolls E with the circular series of foils B and central button A, as shown and described.

This specification signed by me this 28th day of February, 1874.

HENRY BERGER.
